UNITED STATES PATENT OFFICE.

CHARLES THOMAS ODENA AND JOSEPH FRANK JONES, OF HAMPTON,
MISSISSIPPI.

SHOE-FASTENING.

SPECIFICATION forming part of Letters Patent No. 784,419, dated March 7, 1905.

Application filed December 9, 1904. Serial No. 236,180.

To all whom it may concern:

Be it known that we, CHARLES THOMAS ODENA and JOSEPH FRANK JONES, citizens of the United States, residing at Hampton, in the 5 county of Washington and State of Mississippi, have invented new and useful Improvements in Shoe-Fastenings, of which the following is a specification.

This invention relates to shoe-fastenings, 10 such as are designed to secure the ends of shoe-laces in such manner as to prevent the knot thereof from becoming untied or to avoid the necessity of tying a knot.

The objects of the invention are to improve 15 and simplify the construction of such devices; furthermore, to increase their efficiency and operation and to decrease the expense attending their manufacture.

With the foregoing and other minor objects in view, which will appear as the description proceeds, the invention resides in the precise combination and arrangement of parts and in the exact details of construction 20 hereinafter described and claimed as a practical embodiment thereof.

In the accompanying drawings, forming part of this specification, Figure 1 is a view in elevation of a shoe-upper, showing the manner of applying and using the improved fastening. Fig. 2 is a sectional view through the shoe-upper, the improved fastening being shown in side elevation. Fig. 3 is a plan view of the improved fastening with its clamping member open.

35 Like reference-numerals indicate corresponding parts in the different views.

The improved fastening preferably comprises a base-plate 1 and a clamping member 2, which are hinged together in any suitable 40 manner, as indicated at 3. The base-plate 1 is secured to the shoe-upper 4 in any suitable manner—such, for example, as by eyelets or rivets 5.

The clamping member 2 is provided with a 45 spring 6, the terminals 7 8 of which are in engagement with the clamping member, while

the intermediate portions are separated therefrom, as indicated clearly in Fig. 2. In order to reduce the expense attending the manufacture of the device, the spring 6 is formed 50 integral with the clamping member 2 at the end 8 thereof and is bent back upon said clamping member. Upon opposite sides of the integral spring 6 the clamping member 2 is formed with rearwardly-bent tongues 9, surrounding the pin 3, extending through a tongue 10, formed upon the base-plate 1, the tongues 9 9 and 10 and the pin 3 thus constituting means for hinging the clamping member 2 to the base-plate 1. 60

The clamping member 2 is locked to the base-plate 1 in any suitable manner. A convenient form of locking means is illustrated in the drawings as comprising a ball member 11 upon the base-plate 1 and a socket member 12 upon the clamping member 2, said ball-and-socket members 11 and 12 coöperating with each other to hold the clamping member securely in locked position. 65

One convenient method of employing the 70 improved shoe-fastening is illustrated in Fig. 1, from which it will be seen that the shoe-laces are tied in a bow-knot in the usual manner, and the loops and terminals of said laces are extended across the two base-plates 1 and 75 6 of the clamping members 2.

Minor changes in the precise embodiment 80 of invention illustrated and described may be made within the scope of the following claims without departing from the spirit of the invention or sacrificing any of its advantages.

Having thus described the invention, what is claimed as new is—

A shoe-fastening comprising a base member 85 having means to secure the same to a shoe-upper and being formed with an integral tongue, a clamping member having a spring formed integral therewith and bent back thereupon, the two terminals of said spring being in engagement with the clamping member and the intermediate portions being separate there- 90

from, integral tongues upon said clamping members on opposite sides of said integral spring, a pin extending through the integral tongues of the clamping member and through the integral tongue of the base member for hinging the clamping member to the base member, and ball-and-socket means for locking the clamping member to the base member.

In testimony whereof we affix our signatures in presence of two witnesses.

CHARLES THOMAS ODENA.
JOSEPH FRANK JONES.
